DRIVE-IN FOOD PREPARATION BUILDING

Gerald B. Cox, Bettendorf, Iowa, assignor to Yum-Yum
Barns, Inc., Davenport, Iowa

Filed Nov. 18, 1970, Ser. No. 26,067

Term of patent 14 years

Int. Cl. D25—03

U.S. Cl. D13—1

FIG. 1

FIG. 2

FIG. 3

FIG. 4

FIG. 1 is a front perspective view of a drive-in food preparation building embodying my new design.

FIG. 2 is a front elevation thereof.

FIG. 3 is a side elevation thereof, it being understood that both sides of the building are identical.

FIG. 4 is a rear elevation thereof.

I claim:

The ornamental design for a drive-in food preparation building, substantially as shown.
